ARM GUARD FOR ARCHERY

Otto L. Anderson, 354 South 1100 East, and Marvin Naylor, Box 42, both of Springville, Utah 84663

Filed Aug. 1, 1966, Ser. No. 3,297

Term of patent 14 years

(Cl. D2—27)

FIG. 3.

FIG. 4.

FIGURE 1 is a front view of an arm guard for archery embodying our new design, and

FIG. 2 is a side elevational view thereof,

FIG. 3 is an end view as viewed on line 3—3 of FIG. 1 thereof, and

FIG. 4 is an end view as viewed on line 4—4 of FIG. 1 thereof.

We claim:

The ornamental design for an arm guard for archery, substantially as shown.
